ABRASIVE WHEEL WITH FLEXIBLE
RESILIENT RIM

Miles E. Landau, Brooklyn, N. Y.

Application October 15, 1947, Serial No. 730,025

6 Claims. (Cl. 51—194)

1

This invention relates to abrasive wheels and has particular reference to an abrasive wheel having an abrasive rim so constructed and arranged as to permit it to adjust its surface at the place of contact to the contour of the surface of the material being finished, the same being a continuation in part of co-pending application Serial No. 722,454, filed January 16, 1947.

The invention has for an object the provision of an abrasive wheel having a resilient tread forming the rim thereof which is flexibly mounted to permit it to expand when centrifugal effect forces it outward to an extended position from which position any part of it may be depressed or flattened, thus adjusting its abrasive surface to the contour of the work at the place of contact to produce a flat grinding or finishing action.

Another object of the invention is the provision of a tread consisting of an abrasive rim in the form of a resilient and flexible annulus together with tension means for adjustably securing an abrasive belt on the periphery thereof.

The invention has for a further object the provision of a separable flexible abrasive belt adjustably secured upon the periphery of the tread permitting the said belt to expand and contract as changes occur in the tread during operation.

A further object of the invention is to provide a peripheral groove formed into the tread and serving to seat a corresponding rib formed in a separable abrasive belt throughout its entire length, the said rib being held firmly in the groove of the tread during rotation when centrifugal force expands the tread with resultant pressure of the tread against the inner surface of the flexible abrasive belt.

A further object of the invention is to dispense with the separable abrasive belt for certain kinds of work and instead to incorporate into the tread composition suitable abrasive or polishing powder material whereupon the tread itself becomes the abrasive means and requiring replacement when worn out.

With the foregoing and other objects in view reference is now made to the following specification and accompanying drawings in which the preferred embodiments of the invention are illustrated.

In the drawings:

Fig. 1 is a side view of an abrasive wheel constructed in accordance with the invention and illustrating the same with parts broken away to show the underlying construction.

Fig. 2 is a transverse fragmentary sectional view taken approximately on line 2—2 of Fig. 1, showing the wheel casing.

Fig. 3 is a similar view showing the wheel casing and the operating parts in position therein.

Fig. 4 is a sectional view through a rim and belt with interengageable groove and rib.

2

Referring to the drawings by characters of reference, the abrasive wheel includes a casing consisting of oppositely disposed circular side plates 10 and 11 secured to the opposite ends of a hub 12 having an opening therein to receive a driveshaft, the side plates 10 and 11 being spaced apart to provide a circumferentially extending space therebetween. The side plates 10 and 11 have arcuately spaced extensions or projections 13 located adjacent the rims thereof so as to form transversely extending trunnions.

Located between the rims of the side plates is a peripheral tread 14 of annular formation having parallel side faces 15 and 16 and arcuately spaced apertures 17 extending through the opposite side walls thereof through which the trunnions 13 loosely extend for flexibly mounting the tread thereon with the outer periphery of the tread protruding beyond the peripheries of the side plates. The tread is fashioned of flexible resilient material and fits loosely between the side plates while the transverse apertures 17 are of larger diameter than the trunnions 13 to thereby permit of the free movement of the tread on the trunnions.

An annular spring metal band member 18 is located between the side plates in engagement with the inner periphery of the tread to serve as a resilient support therefor. A flexible abrasive belt 19 surrounds the tread and is tensioned thereon by wire yoke members 20 pivotally anchored at their inner ends to inwardly bowed leaf springs 21 secured at their outer ends 22 to the inner face of a rigid annular metal band 23. The yoke members 20 each include opposite side leads 24 and terminal fingers 25 extending transversely from the outer ends of the side leads and engaging in notches 26 formed in the periphery of the tread with the abrasive belt 19 extending into said notches and underlying the terminal fingers therein. The yoke and leaf spring members are quadrantly spaced apart with the yoke members extending through openings 27 in the annular band member 23 and the terminal fingers 25 engaging the abrasive belt 19 at quadrantly spaced locations. The yoke and leaf spring members are freely movable between the side plates 10 and 11 and provide a floating tension means for adjustably securing the abrasive belt 19 on the periphery of the tread so that the same is free to change with the change in circular formation of the tread. By this construction the annular tread 14 is adapted to expand or elongate from circular formation during rotation thereof which permits it to depress or flatten and adjust the periphery at any part thereof with the surface of the material pressed thereagainst in the abrading operation.

Instead of the yoke and leaf spring members, 60 the tread may be formed with a shallow centrally

arranged recess or depression 28 extending continuously about the outer periphery thereof as indicated in Fig. 4 of the drawings. An abrasive belt 29 formed with an inwardly projecting rib 30 extending continuously about the inner periphery thereof is adapted to engage in the recess or depression 28 in the tread for retaining the belt on the tread and preventing sidewise movement thereof.

The tread is preferably fashioned of elastic rubber composition material and the same may be impregnated with an abrasive substance so that the outer periphery of the tread becomes the abrasive surface of the wheel.

What is claimed is:

1. In an abrasive wheel, a circular casing including a hub and opposite side plates disposed in spaced relation and projecting outwardly beyond the hub to provide a circumferentially extending space therebetween, a flexible tread located between said plates with the outer portion thereof protruding beyond the peripheries of the side plates, trunnions carried by said side plates and extending through apertures in said tread for loosely supporting the tread between the side plates and permitting radial movement thereof, an annular spring band freely arranged between said side plates on which the inner periphery of the tread is disposed, an abrasive belt arranged on the outer periphery of said tread, and tensioned means located between the side plates and consisting of yoke members engaging said belt at circumferentially spaced locations about the wheel and pivotally secured to spring members located between the side plates and between the hub and said band member for securing and resiliently tensioning the belt on the tread.

2. In an abrasive wheel, a hub having side plates disposed in spaced relation to provide a circumferentially extending space therebetween, a flexible resilient tread of annular formation mounted between the side plates with the outer peripheral portion thereof protruding beyond the peripheries of the plates, said side plates having arcuately spaced trunnions extending through apertures in the tread for loosely supporting the tread thereon between the said plates and permitting radial movement of the tread, an annular spring band freely arranged between said side plates in surrounding relation with the hub on which the inner periphery of the tread is resiliently supported, said tread having circumferentially spaced notches in the outer periphery thereof, an abrasive belt arranged on the outer periphery of said tread and engaging in said notches, yoke members having transversely extending fingers overlying the belt in said notches, a rigid annular band freely arranged between said side plates and bowed spring members secured at their inner ends to the inner face of said last mentioned band and pivotally connected medially thereof to said yoke members for securing and resiliently tensioning the belt on the tread.

3. In an abrasive wheel, a hub having side plates disposed in spaced relation to provide a circumferentially extending space therebetween, a flexible resilient tread of annular formation mounted between the side plates with the outer peripheral portion thereof protruding beyond

the peripheries of said plates, said side plates having arcuately spaced trunnions extending through apertures in the tread for loosely supporting the tread thereon between the said plates and permitting radial movement of the tread, and an annular spring band freely arranged between said side plates in surrounding relation with the hub on which the inner periphery of the tread is resiliently supported.

10. 4. In an abrasive wheel, a hub having side plates disposed in spaced relation to provide a circumferentially extending space therebetween, a flexible resilient tread of annular formation mounted between the side plates with the outer peripheral portion thereof protruding beyond the peripheries of said plates, said side plates having arcuately spaced trunnions extending through apertures in the tread for loosely supporting the tread thereon between the said plates and permitting radial movement of the tread, an annular spring band freely arranged between said side plates in surrounding relation with the hub on which the inner periphery of the tread is resiliently supported, said tread having circumferentially spaced notches in the outer periphery thereof, an abrasive belt arranged on the outer periphery of said tread and engaging in said notches, and tensioned yoke members having transversely extending fingers overlying said belt in said notches for securing and resiliently tensioning the belt on the tread.

5. In an abrasive wheel, a hub having side plates disposed in spaced relation to provide a circumferentially extending space therebetween, a flexible resilient tread of annular formation mounted between the side plates with the outer peripheral portion thereof protruding beyond the peripheries of said plates, said side plates having arcuately spaced trunnions extending through apertures in the tread for loosely supporting the tread thereon between the said plates and permitting radial movement of the tread, an annular spring band freely arranged between said side plates in surrounding relation with the hub on which the inner periphery of the tread is resiliently supported, an abrasive belt arranged on the outer periphery of said tread and means securing the same thereon against lateral movement.

6. In an abrasive wheel, a hub having side plates disposed in spaced relation to provide circumferentially extending spaces therebetween, a flexible resilient tread of annular formation mounted between the side plates with the outer peripheral portion thereof protruding beyond the peripheries of said plates, said side plates having arcuately spaced trunnions extending through apertures in the tread for loosely supporting the tread thereon between the said plates and permitting radial movement of the tread, an annular spring band freely arranged between said side plates in surrounding relation with the hub on which the inner periphery of the tread is resiliently supported, an abrasive belt engaging about the outer periphery of said tread, and said tread and belt being formed with interengaging peripheral groove and bead for preventing movement of the belt with reference to the tread.
